UNITED STATES PATENT OFFICE.

CLARENCE A. GOUTY, OF BUSHNELL, ILLINOIS.

TROLLEY.

Application filed October 12, 1925. Serial No. 62,085.

The invention relates to trolleys such as are used in connection with electric cars or locomotives.

The purposes of the invention are: To provide a light compact and serviceable trolley which may be produced at a relatively small cost and which shall be flexible and safe in use and in which parts subject to wear may be easily and quickly replaced; to provide a sleet cutter of improved construction in conjunction with the harp of the trolley; and to provide a trolley embodying serviceable improvements safe-guarding the trolley against injury to the electric line on which it operates or to the usual stay wires steading the trolley line.

The present invention is a modification and improvement of the invention set forth in United States Patent No. 1528372, granted to me March 3rd, 1925, for improvement in trolleys.

The invention consists in improved structural details shown in the accompanying drawing, to which reference is hereby made and now to be described and finally recited in the claims.

Figure 1 is a side elevation of a complete trolley embodying my invention; Fig. 2 is a top plan of the same trolley; Fig. 3 is a horizontal section taken on the line 3—3 of Fig. 1; Fig. 4 is a vertical transverse section taken on the line 4—4 of Fig. 1; Fig. 5 is a vertical section through the trolley taken on the line 5—5 of Fig. 2; Fig. 6 is a perspective view of the detached sleet cutter viewed from below; and Fig. 7 is a vertical section on the line 7—7 of Fig. 6. Similar reference numerals and characters refer to similar parts throughout all the views.

I have found by experiment that the trolley shown and described in my said application is subject to the objection that the metallic contacts therein shown and described are insufficient to effectively control the flow of the electric current where high tension is used. I have also found by experiment that the construction shown and described in my said patent is such that excessive rotation of the shoe is likely to occur, thereby placing the shoe in such position that there is danger of the shoe engaging on the stay wires of the trolley line; often resulting in breaking the stay wires and other injury to the trolley line. The main purpose of the present invention is to obviate these objections.

I will first describe in detail the mechani-

cal features which characterize the present invention and will recite in the appended claims the improvements herein set forth.

The harp 6 is a casting having integral upwardly extending lateral curved members 7, adjacent to the forward end of the shoe; the harp has also in its upper part a depression 8 in which the forward part of the shoe 9 is located; and a depression 10 in which a contact spring 12 is located. The spring 12 engages with the under side of the shoe for a large part of the length of the shoe. One terminal part of the spring 12 is secured in the depression 10 by a rivet 19.

The shoe 9 and its spindle 13 are of manganese steel, or other hard metal, smoothly finished and polished to run on the transmission line without undue wear or abrasion of the line. The harp and appurtenances will preferably be made of an alloy. The harp has also a lengthwise chamber 15 containing twin flat springs 16 which bear on flat parts 14 of the spindle 13. One end of each of the springs 15 is secured by a rivet 17 which extends through the body of the harp and through both springs. The free terminals of the springs 16 bear on the inner side walls of the harp.

The spindle 13 has flat parts 14 on which the springs 16 engage in such manner that rotation of the stem serves to stress the springs oppositely and both springs act to restore the shoe to normal position after it has been rotated more or less.

A flat contact spring 18 similar to the spring 12 is secured on the under side of the harp by a rivet 20. Each of the springs 12 and 18 has a transverse hole in which the spindle 13 rotates freely. A nut 22 screws onto the lower terminal part of the stem and is secured by a transverse cotter pin 23.

When the parts are assembled as shown in Figs. 1 and 2, the forward end of the shoe will be in the depression 8 and the members 7 while permitting free oscillation of the shoe within the depression, will prevent such excessive movement as might bring the forward part of the shoe into such position that it might engage with the stay wires of the trolley line. The shoe 9 has a lengthwise groove 21, the upper surface of which, at the front end of the shoe, is approximately in the plane of the inclined part 25 of the harp, in order that the line wire will lie naturally in the groove of the harp without danger of abrasion of the wire by the front end of the shoe.

The double contacts 12 and 18 have sufficient surface to safely conduct high tension current. The form of the groove 21 permits the shoe 9 to travel safely on the wire and to oscillate sufficiently to permit the trolley to run safely around all usual curves in the line; and the members 7 prevent excessive and dangerous oscillation of the shoe.

The sleet cutter is a casting, preferably of manganese-bronze or other obdurate wear-resisting metal and comprises a body 26, lengthwise prongs 27 integral with the body and spaced apart from each other the proper distance to permit the prongs to straddle the harp body, one prong on each side.

Aligned holes 28 in the respective prongs receive a removable pin 29 which extends through a transverse hole 30 (Fig. 5) in the harp body and connects the sleet cutter with the harp body.

The body 26 has an integral downwardly inclined member 31 shaped to fit in the groove 21 of the shoe 9.

The purposes of the member 31 are to support the cutter structure in an upwardly and rearwardly inclined position on the shoe and to form a good electrical contact of the cutter with the shoe.

When the parts are assembled the upper edges of the prongs 27 engage on the laterally extending members 7 of the harp and tend to keep the member 31 in close electrical contact with the shoe 9.

The cutter body 26 has at its free end an arcuate groove 32 to guide the travel of the cutter body on the line wire. The inclined side walls of the groove 32 converge to form a sleet cutting edge 33 (Fig. 7) which bears against the under side of the line wire and cuts the sleet as the cutter travels along the wire. The upper end of the sleet cutter extends upwardly above the rear part of the shoe in order that the sleet, as it is stripped from the line wire will fall clear of the harp thus avoiding excessive arcing.

The sleet cutter will be used only when there is sleet on the line wire.

To detach the sleet cutter from the harp, the bolt 29 will be withdrawn and the cutter will be lifted off the harp, and may be easily and quickly replaced when needed.

The operation of the trolley will be readily understood from the foregoing description.

I am aware of the prior use of springs in a lengthwise chamber of the harp to restore the shoe to straight-forward position after it has been oscillated. I am also aware that contact springs have been used between an oscillating shoe and the body of the harp. I therefore do not claim broadly the use of springs admitting of oscillation of the shoe. I do however, believe that I am first to devise and use stationary means on the harp limiting the scope of oscillation of the forward part of the

shoe; and that I am the first to devise and use a shoe having a lengthwise groove the bottom of which, at the forward end of the shoe, is approximately in the plane of the inclined upper surface of the body of the harp.

Having fully described my invention what I claim as new and desire to secure by Letters Patent is:

1. A trolley comprising a harp, having in its upper part a depression adapted to receive the forward end of an oscillative shoe and a depression adapted to receive a contact plate; said harp having also upwardly and laterally extending members effective to limit lateral movement of the forward part of the shoe; and a shoe above the upper surface of the harp and having its forward part located between the upwardly extending lateral members of the harp.

2. A trolley comprising a harp having in its upper part a depression adapted to receive the forward end of an oscillative shoe and a depression adapted to receive a contact plate; said harp having also upwardly and laterally extending members effective to limit lateral movement of the forward part of the shoe; a shoe above the upper surface of the harp and having its forward part located between the upwardly extending lateral members of the harp; said shoe having also a spindle extending through the harp and a fixed member at the lower end of said spindle; and duplicate contact springs, one engaging on the lower surface of the shoe and the other engaging on said fixed member and constituting two complete electrical contacts of the shoe with the harp, for safe transmission of high tension current.

3. In operative conjunction with a trolley-harp and a non-rotative shoe oscillative on the harp; an ice-cutter comprising a body of obdurate wear-resisting material having lengthwise prongs spaced apart from each other to receive the body of the harp between said prongs; having also a downwardly extended member shaped to enter the groove of the trolley-shoe to support the ice-cutter in upwardly and rearwardly inclined position relative to the shoe and electrically connecting the ice-cutter with the shoe; and having also an inclined groove the walls of which converge to form a cutting edge and are under cut to permit the detached ice to fall clear of the rear end of the trolley; and means detachably connecting the ice-cutter in operative relation to the shoe.

4. In operative conjunction with a trolley-harp having laterally extended members; and a non-rotative shoe oscillative on the harp; an ice cutter comprising a body of wear-resisting material, having lengthwise prongs spaced apart from each other to receive the body of the harp between said prongs; having also a downwardly extending member shaped to form an electric con-

tact in the groove of the shoe; and having an upwardly and rearwardly inclined grooved member having a cutting edge traveling on the under side of the line wire; and a connecting device connecting the prongs of the ice cutter with the body of the harp adjacent to the curved members thereof in such manner that said laterally extended members will prevent upward turning of the sleet cutter and consequent breaking of the electric contact.

5. A trolley comprising a harp having both a depression to receive an oscillative shoe and laterally extended members; a shoe os-

cillative in said depression to an extent limited by said laterally extended members; an ice cutter having lengthwise prongs and a contact member engaging in the groove of the shoe; said prongs of said ice cutter engaging the latterly extending members on said harp to prevent lifting of said contact member and consequent breaking of the contact between the ice cutter and the shoe. 15

In witness whereof, I have hereunto signed my name at Bushnell, McDonough County, 25 Illinois, this 3rd day of Aug. 1925.

CLARENCE A. GOUTY.
